UNITED STATES PATENT OFFICE.

THEODORE FISHLEIGH, OF OSHAWA, ONTARIO, CANADA.

PLAYER-PIANO.

1,319,326.

Specification of Letters Patent.

Patented Oct. 21, 1919.

Application filed November 8, 1918. Serial No. 261,641.

To all whom it may concern:

Be it known that I, THEODORE FISHLEIGH, of the town of Oshawa, in the county of Ontario, in the Province of Ontario, Canada, 5 have invented certain new and useful Improvements in Player-Pianos, of which the following is the specification.

My invention relates to improvements in player-pianos and the object of the invention is to provide adjustable means for changing the tone produced by the player piano to any desired pitch and it consists of the following arrangement and construction of parts as hereinafter more particularly explained.

Figure 1, is a front elevation of my device.

Fig. 2, is a sectional view through the adjustable portion of the control.

In the drawings like characters of reference indicate corresponding parts in the various figures.

1 indicates the base of the mechanism provided with side standard boards 1^x and 1['] between which are mounted in the usual manner the music roll 2 and take-up roll 3. 4 indicates the tracker bar provided with the usual note orifices 4^x. At each end of the note orifices 4^x are located a series of small orifices, the orifices 5, 6, 7, 8, 9, 10 and 11 being located at one end of the series of note orifices and the orifices 12, 13, 14, 15, 16, 17 and 18 at the other end of the note orifices. The tracker bar is slidably supported so as to move longitudinally by the pins 4² and 4³ extending from one end of the tracker bar through a plate 4⁵ secured to the standard board 1['] and at the other end by a pin 4⁶ and rod 4⁷ extending through the plate 4⁸ secured to the standard board 1^x.

40 19 indicates a block supported upon the base board 1 and provided with two series of orifices, one series being designated by the numerals 20, 21, 22, 23, 24, 25, and 26 and the other series by the numerals 27, 28, 29, 30, 31 and 32. The orifices 20, 21, 22, 23, 24, 25 and 26 are connected by tubes 20^x, 21^x, 22^x, 23^x, 24^x, 25^x and 26^x to the orifices 5, 6, 7, 8, 9, 10 and 11 of the tracker bar. The orifices 27, 28, 29, 30, 31 and 32 are 50 connected by tubes 27^x, 28^x, 29^x, 30^x, 31^x, 32^x and 33^x to the orifices 12, 13, 14, 15, 16, 17 and 18 of the tracker bar.

34 and 35 indicate guide bars secured to the block 19 in proximity to its upper and lower edge and provided with rabbet grooves 34^x and 35^x into which fits a slide bar 36.

The slide bar 36 is provided with two orifices 37 and 38. 39 and 40 indicate standard boards carrying pneumatics 41 and 42, the pneumatic 41 being provided with a tongue 41^x and the pneumatic 42 with a tongue 42^x. The tongues 41^x and 42^x are connected together by a link bar 43. The standard boards 39 and 40 are spaced apart and serve to support between the pneumatics 41 and 42 a valve chamber 44. 45 and 46 indicate pouch chambers provided with pouches 47 and 48. 49 indicates a vacuum chamber located above the pouch chambers, in the top board of which are formed vertical 70 orifices 50 and 51 from which extend horizontal orifices 52 and 53 leading to the interior of the pneumatics 42 and 41. 54 and 55 indicate valve stems provided with upper heads 56 and 57 and lower heads 58 75 and 59 from which extend stem extensions 60 and 61 carrying valve buttons 62 and 63 which coact with the pouches 47 and 48. 45^x and 46^x indicate orifices leading into the pouch chambers 45 and 46. 60^x and 61^x indicate tubes connecting the orifices 45^x and 46^x to the orifices 37 and 38. The opposite end of the rod 47 is pivotally connected to the movable portion of the pneumatic 41. 62 indicates a plate provided with a series 85 of recesses 63, 64, 65, 66, 67, 68 and 69. 70 indicates a rod pivotally connected at one end to the slide bar 36 and provided at its opposite end with a button 71, its upper portion being formed into a knob 72 and its 90 lower portion into a projection 73 adapted to fit into one of the recesses 63, 64, 65, 66, 67, 68 or 69.

It will be noticed that the orifices in the tracker bar at each end of the note orifices and each side of the orifices of the block 19 and the recesses in the plate 62 all correspond in number, seven being the number which I preferably use.

Having described the principal parts involved in my invention I will briefly describe the operation of the same.

It will be noticed in Fig. 1 that the strip forming the music roll and passing from the roll 2 to the take-up roll 3 is indicated 105 by dotted lines 74 and 75 forming the edges of the strip. These edges pass centrally normally over the center of the central orifice of each series located at each end of the note orifices of the tracker bar. It 110 will, therefore, be seen that an equal amount of air passes through the orifices 15 and

18 and through the tubes 30^x and 23^x to the orifices 30 and 23, the air passing from thence through the orifices 37 and 38 and through the tubes 60 and 61 into the pouch 5 chambers 45 and 46.

When it is desired to change the tone the operator grasps the knob 72 and lifts the projection 73 out of the recess 66 and passes it into the recess 67 if he desires to raise 10 the tone and into the recess 65 if he desires to lower the tone. We will, however, take as an example the operation when the projection is placed in the recess 67. When this is done the slide bar 36 is moved carrying 15 the orifice 37 and the orifice 38 into alignment with the orifice 24 and orifice 29. When this is done it will be seen that the orifice 9 with which the orifice 24 is connected will be an uncovered orifice whereas 20 the orifice 14 connected to the orifice 29 will be covered by the music strip. It will thus be seen that no air can pass through such orifice 14 to the pouch chamber 46 and that, therefore, the vacuum will then 25 operate to raise the valve stem 54 carrying the head 57 of the valve against the lower end of the orifice 50 thereby cutting off the vacuum from the pneumatic 42 and allowing the air to enter beneath the raised valve 30 head 56 into the pneumatic. The vacuum tension still remains upon the pneumatic 41 which is thereby collapsed exerting a pull on the rod 47 so as to draw the tracker bar over one space until the orifices 14 and 9 35 are partially covered, that is, equal to the width of one note orifice so that the whole series of note orifices are carried over whereby the perforations of the music strip will co-act with a note orifice of a higher 40 tone than before this operation took place. This operation may be continued throughout the whole series of recesses 66, 67, 68 and 69 raising the tone to the maximum pitch. When the projection 73 is moved in 45 the opposite direction to engage with the recesses 65, 64, and 63 the tone is lowered and the tracker bar carried in the opposite direction to that previously described.

From this description it will be seen that I have devised a very simple device whereby 50 the tone produced by a player piano may be raised to any desired pitch by the operator either before or during the playing of a piece.

What I claim as my invention is—

1. In a player piano, the combination with the tracking device comprising a tracker bar having a series of guide holes at each end of the tracker bar and the operating valves and tubular connections 60 between the guide holes and valves, of manually operated means interposed in such tubular connections and between the guide holes and valves for successively rendering a guide hole at each end of the 65 tracker bar operative in pairs.

2. In a player piano, the combination with the longitudinally movable tracker bar, of a series of orifices located at each end of the tracker bar so that each edge of 70 the music strip partially covers the central orifice of each series, pneumatically operated means for moving the tracker bar, a pair of pneumatic valves operating such pneumatic means, and means for connecting the 75 valves successively to any one of the orifices at each end of the tracker bar.

3. In a player piano, a longitudinally movable tracker bar having a series of orifices located at each end of the tracker 80 bar, a block having two corresponding series of orifices, the orifices of the block being connected to corresponding orifices of the tracker bar, a movable slide bar co-acting with the block having one orifice co-acting 85 with each series of orifices of the block, a pair of pneumatic valves, an air duct connecting each orifice of the slide bar with one of the valves, a pair of pneumatics, and a link connection between the pneumatics and tracker bar.

THEODORE FISHLEIGH.
